UNITED STATES PATENT OFFICE.

ROBERT R. HALL, OF MILLBRAE, CALIFORNIA.

DESIGN FOR A BRIDGE FOR SPECTACLES AND EYEGLASSES.

45,418.

Specification for Design.

Patented Mar. 17, 1914.

Application filed August 10, 1912. Serial No. 714,477. Term of patent 14 years.

To all whom it may concern:

Be it known that I, ROBERT R. HALL, a citizen of the United States, residing at Millbrae, county of San Mateo, and State of California, have invented a new, original, and ornamental Design for a Bridge for Spectacles and Eyeglasses, of which the following is a specification, reference being had to the accompanying drawing, forming part thereof.

The drawing is a perspective of the design on a greatly exaggerated scale.

I claim:

The ornamental design for a bridge for spectacles and eyeglasses, as shown.

ROBERT R. HALL.
